CAN PACKAGE
John Alexander Jones, 6312 Fairfield Drive,
Flourtown, Pa.
Filed Jan. 29, 1960, Ser. No. 5,462
4 Claims. (Cl. 206—47)

The present invention relates to packages and has particular application to packages for use with cans of two-cycle engine oil which is normally mixed in predetermined relation with the gasoline to be poured into the tank of the engine.

Motor oil of this character is normally packaged in rectangular cans having a pouring spout or neck adjacent one end in the top wall of the can. Markings have been applied to cans of this type to indicate the angle at which the can should be held in order to dispense the desired quantity of oil. While such a procedure may be satisfactory for use on dry land and when the can is new, it is not satisfactory when in a small boat, or when the can is sufficiently dirty to obscure the markings thereon. It has been the practice of most people to carry along a separate measuring receptacle which is able to receive the necessary amount of oil for pouring into the gas tank of the engine. Frequently, the measuring receptacle is lost or misplaced and it is therefore necessary to revert to the unsatisfactory method used previously for roughly measuring the oil.

With the foregoing in mind, the present invention provides a package for rectangular cans which forms a pocket for receiving a measuring receptacle or the like.

More specifically, the present invention provides a package of a stated type which is highly economical to produce and assemble, but which is fully effective in operation.

All of the objects of the present invention are more fully set forth hereinafter with reference to the accompanying drawings wherein:

FIG. 1 is a view in perspective of a package made in accordance with the present invention;

FIG. 2 is a view similar to FIG. 1 with the package opened and with two containers shown in broken lines to more clearly illustrate the construction and assembly thereof;

FIG. 3 is a sectional view taken on lines 3—3 of FIG. 1; and

FIG. 4 is a detached view in elevation of the measuring receptacle and funnel embodied in the package.

Referring to the drawings, the can package comprises four rectangular containers 11 of any suitable height having a length greater than the width. As shown, each container has front and rear walls 12 and 13, respectively, and side walls 14 and 15. A top wall is provided at 16 which has adjacent the side wall 14 a pouring spout 17 and cap 18. Four of the containers 11 are arranged in a square with the front wall 12 of one container coplanar with and contiguous to the side wall 14 of the adjacent container so that the square has an overall dimension in each direction equal to the sum of the width and the length of the containers 11. By reason of the length being greater than the width, a square pocket is formed centrally within the square which has a dimension in each direction equal to the difference between the length and the width of the containers 11.

In accordance with the invention, a measuring receptacle 21 is mounted within the square pocket formed by the assembled containers 11. The measuring receptacle 21 may have any suitable dimensions, but it is preferred that it be circular in cross-section having a diameter equal to the width of the square pocket so that it is snugly received therein. The receptacle 21 may have suitable index markings 22 thereon to indicate the volume of oil

2

within the receptacle when the level of the oil is coincident with the respective indexes 22. A funnel 23 may also be included in the pocket to facilitate pouring of the contents from the receptacle into the gas tank or other reservoir in which the gas is to be mixed with the oil. Preferably, the funnel comprises a neck portion 24 merging into a conical body portion 25 having a cylindrical skirt 26 which telescopically engages over the top of the measuring receptacle 21. When engaged on the receptacle 21, the assembly of the receptacle and funnel preferably has a height corresponding to the height of the containers 11 to limit vertical displacement of the measuring assembly within the assembly of containers.

The assembly may be enclosed in any suitable wrapping, but I prefer to use a wrap-around sleeve 30 having a base 31, side walls 32 and 33, and cover flaps 34 and 35. The base 31 is provided with a pressed-out tongue 36 adjacent each side thereof to prevent inadvertent outward displacement of the containers 11 from the package. The cover flaps 34 and 35 are adapted to overlap one another on top of the assembly and are held in place by snapping over the caps 18 for the pouring spout 17. To this end, the under flap 35 is provided with openings 37, 37 which snap over the caps 18 adjacent the side panel 33. The top flap 34 is provided with a pair of apertures 38 adjacent the side panel 32 to snap over the remaining two caps 18 and apertures 39 which snap over the first mentioned caps above the flap 35. It is noted that the flap 35 is one half of the width of the flap 34 and its free terminal edge is provided with a handle portion 41 which projects upwardly through a central slot 42 in the top flap 34. The overlapping relation of the flaps 34 and 35 and the snap-on engagement of the apertures with the caps, cooperate with the tongues 36 to anchor the sleeve in place without the necessity for extraneous fastening means. By reason of this construction, the package may be opened and closed repeatedly without excessive wear or other damage to the wrap-around sleeve 30.

The particular arrangement of containers 11 in the assembly, and the use of a wrap-around sleeve such as shown at 30 exposes a front wall 12 and a side wall 14 at each side of the package, thereby enabling the purchaser to read the labels on the containers without disassembling the package. The side panels 32 and 33 of the wrapper 30 provide unobstructed space for additional advertising matter or instructions since the brand identification of the containers 11 is readily apparent from the front walls 12 and side walls 14 which are exposed at opposite sides of the package.

While a particular embodiment of the present invention has been herein illustrated and described, it is not intended to limit the invention to such disclosure but changes and modifications may be made therein and thereto within the scope of the following claims:

I claim:

1. A package of four similar generally rectangular containers having a length greater than their width, said containers being arranged in a square with the front wall of each container coplanar with and contiguous to a side wall of an adjacent container, said square having in each direction a dimension equal to the sum of the width and length of the rectangular containers, said containers forming a central square pocket therein having a dimension in each direction equal to the difference between said length and width, a measuring means received in said pocket, and wrapping means retaining said containers and measuring means in assembled relation.

2. A package according to claim 1 wherein said measuring means comprises a receptacle having a width corresponding to the width of said central pocket and including a funnel mounted in said pocket on said measuring recep-

tacle, the combined height of said receptacle and funnel corresponding to the height of said containers, whereby said receptacle and funnel are snugly received in said pocket.

3. A package according to claim 2 wherein said measuring receptacle is cylindrical in form having a diameter equal to the difference between the length and width of said containers, said funnel comprising a neck portion merging into a conical body portion having a cylindrical skirt adapted to telescopically engage over said receptacle, 10 said receptacle having index means thereon to indicate the quantity of material therein.

4. A package according to claim 1 wherein said wrapping means comprises a wrap-around sleeve exposing opposite sides of said assembly and means to anchor said sleeve in place on said assembly.
